CARLYLE W. THOMAS AND FREDERICK E. BRADLEY, OF BRIDGEPORT, CONNECTICUT,
ASSIGNORS TO THE SINGER MANUFACTURING COMPANY, A CORPORATION OF
NEW JERSEY.

SEAM-MARGIN-OPENING DEVICE FOR SEWING-MACHINES.

1,365,747.

Specification of Letters Patent. Patented Jan. 18, 1921.

Application filed March 11, 1918. Serial No. 221,840.

To all whom it may concern:

Be it known that we, CARLYLE W. THOMAS and FREDERICK E. BRADLEY, citizens of the United States, residing at Bridgeport, in the county of Fairfield and State of Connecticut, have invented certain new and useful Improvements in Seam - Margin - Opening Devices for Sewing-Machines, of which the following is a specification, reference being

had therein to the accompanying drawings.

This invention relates to an improvement in devices adapted to open the stitched margins of two superposed pieces of material, and has for an object to provide a simple but effective construction adapted to stitch, trim and open the stitched and trimmed margins during the progress of the material through the machine.

Another object of the invention is to provide a presser-foot with means to separate the margins of two superposed pieces of material and fold back one of said margins.

The invention comprises stitch-forming and trimming mechanisms of well known construction and including a presser-foot having a spring-tongue projecting forwardly from the heel portion of the tread-surface thereof. This spring-tongue is adapted to act as a dividing plate for the marginal portions of the fabrics to be united. The heel portion of the foot is slotted and curved in the form of a guiding scroll, which coöperates with a tongue to fold back the margin of the upper ply after it is stitched and trimmed and is also formed with a shoulder to direct the margin of the lower ply downwardly into a slot formed in the throat-plate, thereby opening out the margins and facilitating the ironing-out of the same after the stitch-forming operation is completed.

In the accompanying drawings, Figure 1 is an end elevation of a portion of a sewing machine embodying the present improvement. Fig. 2 is a view in elevation and partly in section of the mechanism illustrated in Fig. 1, but as viewed in the opposite direction. Fig. 3 is a perspective view of the throat-plate and feed-dogs of the sewing machine. Fig. 4 is a side elevation of the improved presser-foot. Fig. 5 is a bottom plan of the presser-foot. Fig. 6 is a rear end elevation of the presser-foot and

illustrating the stitched, trimmed, and folded material as it issues therefrom. Fig. 7 is a sectional view of the product of the machine, but with the two plies of material opened ready for ironing. Fig. 8 indicates the result of ironing-out the margins of the strip, which is facilitated by the present improvement.

Referring to the drawings, the sewing machine is constructed with a cloth-plate 1, into which is fitted the front slide-plate 2 and the throat-plate 3. The throat-plate is slotted as usual for the passage of the feed-dog 4, carried by the feed-bar 5, which may be actuated in any suitable manner. The stitch - forming mechanism of the sewing machine is of well known construction, including a needle 6, carried by a needle-bar 7 and a coöperating loop-taker 8, the construction and operation of which are unessential to an understanding of the present invention.

Opposed to the feed-dog is a presser-foot 9, secured to the usual presser-bar 10. A portion 11 of the tread-surface of the presser-foot is partly cut away to provide clearance for a resilient tongue 12, spaced slightly from said under-cut surface and formed at its forward end into a transverse material dividing plate 12'. The tongue projects forwardly from a supplemental presser-plate 13, secured by means of a screw 14 to the rear portion of the presser-foot so as to have its lower surface in alinement with the tread-surface of the presser-foot. A folding scroll 16 is formed in the plate 13 and merges at one end into the edge of the tongue 12 and at the other end into the edge-turning wall 17. The presser-plate 13 is provided with a shoulder 18 for a purpose hereinafter explained.

The trimming mechanism comprises a stationary or ledger blade 19 formed in the throat-plate and a movable blade 20 secured by means of a screw 21 to the trimmer-blade carrier 22, mounted on a rock-shaft 23 supported in suitable bearings formed in the bracket 24 projecting upwardly from the cloth-plate of the machine. To the rock-shaft is secured an arm 25 having a fork embracing an eccentric 26 on the actuating shaft 27, and by means of which the trimmer is vibrated.

In operation, two superposed pieces of material are passed underneath the presser-foot to the stitch-forming mechanism and upon opposite sides of the resilient tongue 12, i. e., one above and one below said tongue. After being united by the stitches, the margins of the material are acted upon by the trimmer-blade 20 and severed closely adjacent to the edge of the tongue 12. As the 10 trimmed margin m of the stitched upper ply is fed forward by the feed-dog, it abuts against the folding scroll 16 and is turned upwardly and folded back upon itself. The margin m' of the lower ply is directed downwardly by the shoulder 18 with the co-operative action of the feed-dog, as illustrated in Fig. 6, the edge of the material being free to enter a slot 28 formed in the throat-plate 15 adjacent the feed-dog. The result of folding the edges of the material is illustrated in Fig. 7 of the drawings with both materials opened out. The present improvement therefore obviates the distinct operation heretofore necessary of folding back 20 the stitched margins prior to ironing-out the same to obtain the product indicated in Fig. 8 of the drawings.

Having thus set forth the nature of the invention, what we claim herein is—

- 30 1. In a sewing machine, in combination, stitch-forming mechanism for uniting the margins of a plurality of superposed plies of material, feeding mechanism, and means for folding back one of the united margins in the operation of uniting the same.
2. In a sewing machine, in combination, stitch-forming mechanism for uniting the margins of a plurality of superposed plies of material, feeding mechanism, trimming mechanism for trimming said margins, and means for folding back the united margins.
- 40 3. In a sewing machine, in combination, stitch-forming mechanism for uniting the margins of a plurality of superposed plies of material, feeding mechanism, and a presser-foot including a folding device for folding back one of the united margins in the operation of uniting the same.
- 50 4. In a sewing machine, in combination, stitch-forming mechanism for uniting the margins of a plurality of superposed plies of material, feeding mechanism, a presser-foot, a material-dividing tongue sustained by said presser-foot, and means for folding back one of the united margins in the operation of uniting the same.
- 55 5. In a sewing machine, in combination, stitch-forming mechanism including a needle, feeding mechanism, and a presser-foot

having a folding scroll in the rear of the point of seam-formation.

6. In a sewing machine, in combination, stitch-forming mechanism for uniting a plurality of superposed plies of material, feeding mechanism, means for trimming the 65 margins of said material, and a presser-foot having a folding scroll in the rear of the point of seam-formation.

7. In a sewing machine, in combination, stitch-forming mechanism for uniting a 70 plurality of superposed plies of material, feeding mechanism, a presser-foot, and a material dividing tongue sustained by said presser-foot and spaced from the tread-surface thereof, one edge of said tongue merging into a folding scroll for folding back 75 one of the united margins.

8. In a sewing machine, in combination, stitch-forming mechanism for uniting a plurality of superposed plies of material, 80 feeding mechanism, trimming mechanism, a presser-foot, a supplemental presser-plate secured to said presser-foot, a material dividing tongue projecting forwardly from said presser-plate, and a folding scroll 85 formed in said presser-plate and co-operating with said tongue to fold back one of said united margins.

9. In a sewing machine, in combination, stitch-forming mechanism for uniting the 90 margins of two superposed plies of material, an edge folding scroll in the rear of the point of seam-formation for upwardly directing and folding back one of said margins, and means for downwardly directing 95 the other margin.

10. In a sewing machine, in combination, stitch-forming mechanism for uniting the margins of a plurality of plies of material, and means for opening said united margins 100 in the operation of uniting the same.

11. In a sewing machine, in combination, stitch-forming mechanism for uniting the margins of a plurality of plies of material, a feed-dog, and an edge-deflecting surface 105 co-operating with said feed-dog to fold back one of said margins after they are united.

12. In a sewing machine, in combination, stitch-forming mechanism for uniting the margins of a plurality of plies of material 110 a presserfoot having an edge-deflecting shoulder and a feed-dog co-operating with said shoulder to fold back one of said margins after they are united.

In testimony whereof, we have signed our 115 names to this specification.

CARLYLE W. THOMAS.

FREDERICK E. BRADLEY.
